ATTORNEY.

UNITED STATES PATENT OFFICE.

CHARLES W. JENKS, OF PHILADELPHIA, PENNSYLVANIA.

HANDLE FOR POCKET-BOOKS AND SATCHELS.

SPECIFICATION forming part of Letters Patent No. 227,692, dated May 18, 1880.

Application filed January 5, 1880.

To all whom it may concern:

Be it known that I, CHARLES W. JENKS, of the city and county of Philadelphia, and State of Pennsylvania, have invented a new and useful Improvement in Handles for Pocket-Books, Satchels, &c., which improvement is fully set forth in the following specification and accompanying drawings, in which—

Figure 1 is a side elevation of a pocket-book embodying my invention, the book being shown dotted. Fig. 2 is an end view thereof. Fig. 3 is a section of the frame thereof in line $\alpha\alpha$, Fig. 2. Figs. 4 and 5 are end views of modifications.

Similar letters of reference indicate corresponding parts in the several figures.

My invention consists of an improved pocket-book having a vertical sliding handle connected to its ends, adapted to slide on guides attached to the ends, as hereinafter fully set forth.

Referring to the drawings, A represents a pocket-book, and B a handle, which, in the present case, consists of side pieces, a , and a top connecting-piece or handle proper, b , thus forming a three-sided figure, which may, however, be of curved form.

The ends of the side pieces, a , are connected to the ends of the frame of the pocket-book by means of tongues and grooves, pins and slots, or other guides, so that said pieces slide on the ends of the frame, and the cross-piece b occupies a position against or above the frame or the central part of the pocket-book relatively to the folded or unfolded position of the handle.

The operation is as follows: When it is desired to carry the pocket-book by the handle,

the latter is drawn out to its full extent, the limit being stops suitably applied, the part b thus projecting from the body of the book so as to be readily grasped, as shown by the dotted lines, Fig. 1, and conveniently carry the book.

When the handle is not required for service, or the book is to be placed in the pocket or elsewhere, the handle is moved in to its full extent and folds snugly against the body of the book.

In cases where the book opens at the sides—say as in Figs. 4 and 5—the handle is jointed to the sides of the central brace or guard, d , of the book, the ends of the brace or guard being connected to the axial pins of the jointed frame of the book, or to one section of said frame.

If desired, the sides of the frame and side pieces of the handle may be tubular and enter each other telescopically, or tubes may be placed within the body of the book instead of at the sides, and receive the sliding sides of the handle without producing different results from that stated.

The adaptability of the handle to a satchel, cabas, &c., is apparent.

Having thus described my invention, what I claim as new, and desire to secure by Letters Patent, is—

The improved pocket-book having a vertical sliding handle connected to its ends, adapted to slide on guides attached to the ends, as shown and described.

CHARLES W. JENKS.
